UNITED STATES PATENT OFFICE.

THEODORE H. KRUEGER, OF BRIDGEPORT, CONNECTICUT.

MOISTENING DEVICE FOR GUMMED TAPE, LABELS, AND THE LIKE.

1,312,486.

Specification of Letters Patent.

Patented Aug. 5, 1919.

Application filed October 3, 1917. Serial No. 194,470.

To all whom it may concern:

Be it known that I, THEODORE H. KRUEGER, a citizen of the United States, residing in Bridgeport, county of Fairfield, 5 State of Connecticut, have invented certain new and useful Improvements in Moistening Devices for Gummed Tape, Labels, and the like, of which the following is a specification.

10 My invention relates to moistening devices generally and comprehends the provision of a moistening element, constructed and arranged to yield or give under pressure of the thumb or hand of the user to render that covered portion functionless upon the application of gummed tape thereto but which at the same time will effectively moisten the gummed surface not covered by the user's thumb, and which will 15 thereafter function to moisten the entire surface of the tape when the moistening element is released by the withdrawal of the user's thumb or hand.

To the accomplishment of these and other 20 objects, which will manifest themselves upon a reading of the following specification, I have illustrated in the accompanying drawings several preferable specific embodiments 25 of my invention, by way of example, in 30 which

Figure 1 is a perspective view of a moistening device showing one manner in which gummed tape may be moistened according to the principles of my invention.

35 Fig. 2 is a diagrammatic view illustrating a fragmentary end portion of the gummed tape illustrated in Fig. 1, showing the gummed side thereof moistened.

40 Fig. 3 is an enlarged top plan view of the moistening device shown in Fig. 1.

Fig. 4 is a vertical cross sectional view of the centrally-located yieldable moistening element employed in the device illustrated in Figs. 1 and 3.

45 Fig. 5 is a view in front elevation of a modified form of moistening device partly broken away and in section to more clearly illustrate its construction.

50 Fig. 6 is an end view of the yieldably mounted moistening element employed in the construction shown in Fig. 5.

Figs. 7, 8, 9, 11, 13 and 14 illustrate in 55 front elevation and plan, respectively, certain other modified embodiments of the principles of my invention.

Fig. 10 is a cross sectional view taken on line A—A of Fig. 9.

Fig. 12 is a cross sectional view taken on line B—B of Fig. 11.

Fig. 15 is a cross sectional view taken on line C—C of Fig. 14.

Referring to Figs. 1 and 2 in detail, it will be observed that I have illustrated the principles of my invention as applied to moistening the gummed surface of tape 65 which is indicated by the numeral 1. Manifestly, however, the invention may be used to equal advantage and with corresponding results in connection with gummed labels, sheets, strips and the like. Where it is desired to moisten tape, whether it be in roll or package form, the tape is preferably housed within a magazine or dispensing device 2, provided with a slot through which it can be withdrawn for use. Immediately 70 adjacent the slotted end of the dispensing device is arranged a moistening device, which in the form illustrated in Figs. 1 and 3 comprises a liquid container in which is revolvably mounted upon a shaft 4, a series 75 of moistening elements 5, 6, 7 in the form of cylinders or drums, the surfaces of which convey moisture to the tape when drawn thereover.

As one of the important features of my 85 invention is to provide means whereby that portion of the gummed surface of the tape, which is engaged by the thumb or finger of the user, will remain dry while the remainder of the gummed surface is properly moistened. I provide a yielding surface preferably located in the center of the device so that the thumb of the user while applying the tape to the moistening elements, will cause the contacting surface to give or yield 90 while the adjacent moistening surface will engage and moisten the remainder of the gummed surface of the tape. Various means may be employed for accomplishing this result. In Fig. 3, I employ a soft rubber 100 skeletonized moistening element 6 provided with apertures 8 extending therethrough. The peripheral surface of this element will give under pressure of the thumb when applied thereto as illustrated in Fig. 1, in 105 which it will be noted that the centrally located moistening element has been depressed at that portion engaged by the thumb so that the adjacent zones of the tape laterally of the operator's grasp are enabled to contact 110

with the peripheries of the non-yielding adjacent elements 5 and 6. The result of this manipulation will leave the gummed surface of the strip unmoistened at 9 (see Fig. 2), 5 while the remaining portion of the gummed surface will be properly moistened. Immediately upon the passage of the thumb from the device, thus relieving the pressure from the yieldable surface, that surface regains its normal position and activity as a 10 moistening means with the result that the tape throughout its entire width becomes moistened in a manner thought to be obvious.

Other means may be employed for accomplishing this result and in Fig. 5, I have shown a modification in which moistening elements 10, 11 and 12 are used. The elements 10 and 12 are revolvably mounted upon centrally located element 11, which is of the 20 walls of the liquid container 3, while the centrally located element 11, which is of the same structure as the adjacent element, is revolvably mounted upon a shaft 14, the latter being mounted in a yoke 15 pivotally mounted to swing on a shaft 16, the ends of which are supported in the sides of the liquid container 3. In order to maintain the element 11 in normal moisture applying position, a spring 17 is employed for the purpose. The element 11 in this instance need not be of an inherently yielding character such as the skeletonized element 6 of Fig. 3, owing to this manner of mounting.

It will be apparent that upon the application of pressure by the thumb of the user when drawing tape over the moistening device, the entire element 11 and supporting yoke will be depressed and caused to swing or oscillate on the shaft 16 thus removing it 40 and preventing interference with the moisture applying surfaces of the adjacent elements. When the end of the tape has been fed past, the element 11 will rise under the power of the spring 17, and assume its normal aligned position adjacent to the elements 10 and 12 in moisture applying position.

In Fig. 7 is illustrated a still further modified form of device in which elements 18, 19 and 20 are used, elements 18 and 20 being mounted on short stud shafts 21 mounted in the walls of the liquid container 3, while the intermediate element 19 is mounted upon and supported by an elastic or yieldable member 22. The operation of 55 this form of device is much the same as that illustrated in Fig. 5, excepting that it is somewhat smaller and of less complicated construction. It is obvious that when the element 19 is depressed by the thumb of the user, the member 22 will give so as to permit its descent and upon its release it will automatically regain its normal moisture applying position. In order that the movement of the element 19 may be substantial, 60 I have found it desirable to provide counter-

sinks 23, so that the full elasticity of the member 22 may be taken advantage of.

In Fig. 8, I have shown a still further modification of the invention, in which I use but two moistening elements 24 and 25, 70 the member 24 being either yieldably mounted as a whole, such as shown and described in connection with Figs. 5 and 7, or being provided with a peripheral yieldable portion such as illustrated in Fig. 3. In operating 75 this form of device, the tape is grasped at one side along the longitudinal edge thereof, thus shifting that unmoistened portion of the tape to one side as indicated in dotted outline at 9^a Fig. 2.

It is also possible to effect the desirable results from the structure shown in Fig. 9, where a single or unitary moistening element is employed. This element consists of a single hollow drum 26 journaled in the 85 sides of the liquid container 3, having a peripheral wall 27 made of suitable grade and thickness of rubber or other yieldable material, so that the portion engaged by the thumb may be depressed.

In Figs. 11 and 12 I have illustrated a device in which I employ a yieldable element in the form of a brush 28. This brush is removably inserted in a reservoir 3, the upper end thereof normally projecting above 95 the reservoir and in alignment with the top surface of the adjacent moistening elements 29 and 30. Capillary attraction causes the water from the reservoir to work its way up between the bristles, which are as a consequence maintained in a moist condition so long as there is water in the reservoir. It will be obvious that the thumb of the hand pulling the tape causes the bristles to yield or bend thus permitting the adjacent 105 gummed zones of the tape to contact with adjacent bristles which are not flexed. I may also to equal advantage employ bristles in the place of the cylindrical elements 29 and 30 and I have shown such a structure in 110 Fig. 13, in which removable brushes 31, 32 and 33 are employed.

In Figs. 14 and 15, I have illustrated a moistening device, each element of which is made up of a multiplicity of thin circular 115 disks 34, each separated from its adjacent disk by a thin spacing washer 35. Each group of disks is mounted upon a shaft or spindle 36. The spaces between the adjacent disks are so small that when revolved 120 the liquid will be carried by capillary attraction to the surface of the applied gummed strip of tape and thus effectively moistens it as it is drawn thereacross. The middle group of disks is preferably mounted upon 125 a yoke 37 pivoted at 38 thus enabling it to be depressed in much the same manner as the centrally located moistening element of the construction illustrated in Fig. 5. In order to return the moistening element to 130

its initial active moisture applying position, I employ a compression spring 39 for the purpose.

From the foregoing, it will be noted that in all of the devices illustrated and described is provided a yieldable surface or member which may be rendered temporarily inactive as a moisture applier to that portion of the tape covered by the thumb of the user, and when the thumb is withdrawn the yielding surface of the member or element immediately regains its moisture applying position where it can again become active in moistening the tape.

While I have illustrated and described certain preferred specific embodiments of the principles of my invention, I do so by way of example only, wishing it to be understood that I desire to cover the said principles in whatever form they may find embodiment.

Having thus described my invention what I claim as new herein and desire to secure by Letters Patent is:

1. A moistener for gummed tape including moistening means of a length not less than the width of the tape and across which the tape is drawn, a portion of the moistening means being yieldable independently of other parts thereof so that said yieldable portion can be moved out of operative position leaving the other parts in operative position.

2. A moistener for gummed tape, including rotary moistening means of a length not less than the width of the tape and across which the tape is drawn, a portion of the periphery of the rotary moistening means being yieldable independently of other parts thereof so that said yieldable portion can be caused to function without interfering with the operation of the other parts of the rotary moistening member.

3. A moistener for gummed tape including a cylindrical moistening means mounted to rotate about its longitudinal axis and of a length not less than the width of the tape, a portion of the moistening periphery of the cylindrical moistening element being yieldable under pressure independently of other parts of the moistening means, so that

the yieldable portion can function while the other parts of the moistening element remain in operative position.

4. A moistener for gummed tape, including a series of independent moistening elements having a length not less than the width of the tape and across which the tape is drawn, one of the moistening elements being yieldably supported so that it is bodily movable independent of the other moistening elements.

5. A moistener for gummed tape including a series of moistening rollers across which the tape is drawn, one of the moistening rollers being yieldably supported so that it can be moved into inoperative position without interfering with the other moistening rollers.

6. A moistener for gummed tape, including a series of moistening rollers, a yieldable support for one of the moistening rollers, and fixed supports for the other moistening rollers, the yieldably supported moistening roller being movable into inoperative position independently of the fixedly supported moistening rollers.

7. A moistener for gummed tape including a series of independent moistening rollers, a swinging yoke upon which one of the rollers is journaled, fixed supports for the other rollers, and yielding means acting upon the swinging yoke to hold the roller thereon normally in operative position, the yieldably supported roller being movable into inoperative position independently of the fixedly supported rollers.

8. A moistener for gummed tape including a plurality of independent moistening rollers, a movable support on which one of the rollers is journaled, and yielding means acting upon the movable support to hold the roller mounted thereon normally in operative position, the said roller being movable into inoperative position independently of the other rollers.

9. A moistener for gummed tape including a plurality of moistening rollers across which the tape is drawn, one of the rollers being mounted to yield independently of the other rollers.

THEODORE H. KRUEGER.
